FIG. 3.

INVENTOR.

R. R. NURSE.
by Fred B. Seaman, Inventor

UNITED STATES PATENT OFFICE.

RICHARD ROBINSON NURSE, OF MILLBROOK, ONTARIO, CANADA, ASSIGNOR TO MARY ELIZABETH MILLIGAN, OF MILLBROOK, CANADA.

SIDE ROLLER-CURTAIN FOR VEHICLE AND LIKE TOPS.

No. 926,589.

Specification of Letters Patent.

Patented June 29, 1909.

Application filed April 18, 1908. Serial No. 426,878.

To all whom it may concern:

Be it known that I, RICHARD ROBINSON NURSE, of Millbrook, in the county of Durham, in the Province of Ontario, Canada, 5 have invented certain new and useful Improvements in Side Roller-Curtains for Vehicle and Like Tops, of which the following is the specification.

My invention relates to improvements in 10 side roller curtains for vehicle and like tops, and the object of the invention is to devise a form of side curtain, which will be compact, durable and will contract into small space out of the way.

15 A further object is to make the curtain easily manipulated, convenient and adapted for all kinds of weather.

To effect these objects my invention consists of a jointed reach attached to the interior of the top on the front and rear bows, a 20 roller journaled in bearings forming part of the rear portion of the jointed reach and having a curtain secured thereto designed to be rolled thereupon, a supplemental curtain secured 25 at the top on a rod normally located within a slot in the aforesaid roller and designed to be slidable toward the front, so as to form an extended side curtain, the parts being arranged and constructed in detail as 30 hereinafter more particularly explained.

Figure 1, is a perspective view of portion of the inside of a top showing the bows elevated and the material of the top removed and my invention in position on one side of 35 the top. Fig. 2, is a similar view with the bows thrown back. Fig. 3, is a sectional side elevation showing the top raised. Fig. 4, is a detail of the reach with the roller and curtain. Fig. 5, is a perspective detail showing the 40 joint of the jointed reach broken for folding. Fig. 6, is a detail showing the manner of journaling the roller and of winding the spindle of the same to increase the tension of the spring therein. Fig. 7, is a cross section of the 45 roller.

In the drawings like characters of reference indicate corresponding parts in each figure.

A is the bottom rail, which is fitted on to 50 the top edge of the seat of the buggy or other vehicle.

A' is the goose neck connected to the front of the rail A.

B is the main bow, which is journaled on

the goose neck A' and C is the front bow pivoted 55 on the bow B.

D is an intermediate bow pivoted on the bow B and E is the rear bow.

I do not show the ordinary material, which is attached to the bows B C D and E as it is 60 not necessary for the understanding of my invention.

I preferably use instead of the jointed reach generally used in buggy tops an inner 65 jointed reach F, of the usual construction and pivoted at the front to the bracket G secured to the side of the bow C near the top and at the back to the bracket H secured underneath the top of the rear bow.

F' is an extension bracket attached to or 70 forming part of the rear portion F² of the jointed reach F.

F³ is a bracket attached to or forming part 75 of the rear portion F² of the jointed reach. The bracket F³ is suitably secured to the rear of the joint and extends forwardly as indicated.

In the brackets F' and F³ the roller I is journaled, such roller being provided with a U-shaped crank end I' on the end of the 80 spindle, which is the winding spindle (see Fig. 6). The tail I² normally extends to one side of the bracket F' as indicated and by drawing the crank end I' and holding the roller I from rotating the spring on the inside 85 of the roller, which is of the ordinary type used in spring rollers, may be wound up, so as to get the desired degree of tension to insure of the raising of the curtain I⁴. The crank I' is then pushed backwardly, so as to 90 hold the tension. This crank shaped end is used instead of the ordinary box and square ended spindle fitting in the corresponding orifice in the bracket which is generally used in this class of rollers. The bracket F³ has a 95 curved stop lug F⁴ against which the front end F⁵ of the jointed reach F is designed to come in contact, so as to hold the reach F rigid when in the straight position, and consequently the bracket securely. 100

In Figs. 3 and 4 I have shown the curtain I⁴ drawn off the roller and in these figures it will be seen that the roller I is provided with a slot 2 in which fits a rod 3 having an eye-shaped end 4. The eye-shaped end extends 105 slightly beyond the end of the slot and the rod 3 fitting within the slot is of a greater diameter than the slot and carries the sup-

plemental curtain I^5 . The eye 4 is designed to be secured on a button 5 on the front bow.

If it is desired to have the curtain in the buggy just the same width as the curtain I^4 the curtain I^5 is left in the position shown in Fig. 4, that is behind the curtain I^4 , but should it be stormy all that is necessary to do is to catch hold of the eye 4 and pull the rod forwardly into the position shown in dotted lines in Fig. 4, and in full lines in Fig. 3. In this position both curtains may be lowered as shown in Fig. 3, so as to exclude very much more of the storm than were the curtain only of the width of the curtain I^4 alone. To draw up the curtain, of course, the rod 3 is always pushed backwardly into the recess in the roller, within the slot 2 and by pulling upon the curtain I^4 both curtains may be rolled up, the curtain I^5 rolling up on the roller I within the curtain I^4 .

In Fig. 2, when the top is thrown back and the joint of the reach F broken the curtain on both sides of the top will be located as indicated in this figure and entirely out of the way.

Such a side curtain as I describe is very convenient, compact and is entirely out of the way when not in use.

What I claim as my invention is:

1. In a side roller curtain for vehicle and like tops, the combination with a jointed side reach suitably secured at the side of the top and movable horizontally inward, of a roller and side curtain held thereon journaled in bearings attached to the said reach as and for the purpose specified.

2. In a side roller curtain for vehicle and like tops, the combination with a jointed side reach and end brackets to which the said reach is pivotally connected, said brackets being secured on the inside of the front and back bows, said reach having horizontal movement of a roller journaled in bearings in the side reach and a curtain attached thereto as and for the purpose specified.

3. In a side roller curtain for vehicle and like tops, the combination with a jointed side reach having horizontal movement and secured on the inside of the front and back bows, of extension brackets secured to the front and back of the rear portion of the jointed side reach and a roller journaled in

the same and carrying a side curtain as and for the purpose specified.

4. In a side roller curtain for vehicle and like tops, the combination with a jointed side reach and end brackets to which the said reach is pivotally connected, said brackets being secured on the inside of the front and back bows, of extension brackets secured to the front and back of the rear portion of the jointed side reach, the forward bracket being provided with a lug and a roller journaled in the same and carrying a side curtain as and for the purpose specified.

5. In a side roller curtain for vehicle and like tops, the combination with a jointed side reach and end brackets to which the said reach is pivotally connected, said brackets being secured on the inside of the front and back bows, of extension brackets secured to the front and back of the rear portion of the jointed side reach, and a roller journaled in the same and carrying a side curtain and provided with a slot and a longitudinal recess and rod fitting in the longitudinal recess and carrying a curtain as and for the purpose specified.

6. In a side roller curtain for vehicle and like tops, the combination with a jointed side reach and end brackets to which the said reach is pivotally connected, said brackets being secured on the inside of the front and back bows, of extension brackets secured to the front and back of the rear portion of the jointed side reach, and a roller journaled in the same and carrying a side curtain and provided with a slot and a longitudinal recess and rod fitting in the longitudinal recess and carrying a curtain and having an eye at the front end to engage with a button on the front bow when the rod is extended as and for the purpose specified.

7. In a device of the class described, a roller having a curtain attached to the same and provided with a longitudinal slot, a rod fitting in the slot and carrying a supplemental curtain and movable lengthwise out of the roller as and for the purpose specified.

RICH'D. ROBINSON NURSE.
